CONDUIT FOR PROJECTING SAND

Application filed March 2, 1929, Serial No. 344,082, and in Germany December 12, 1928.

Our invention relates generally to machines for projecting sand by means of compressed air, such as sand molding machines, and is especially directed to improvements in the conduit through which the sand and air current passes to the nozzle through which the mixture of sand and air issues.

The conduit is usually in the form of a pipe or hose whose internal diameter must be sufficiently large to avoid presenting excessive resistance to the current of sand and air flowing therethrough. At the outlet end of the conduit the speed of this current must be suitably increased in order to attain the requisite velocity for projecting the sand and compacting it into the molds. It has been proposed, heretofore, to bring about this increased speed of the sand and air current by inserting in the conduit at or near its outlet end a section of pipe having a bore of smaller diameter than that of the conduit itself, but this expedient proved to be undesirable because the inserted section of pipe impeded the flow of air and frequently caused choking of the conduit.

The object of our invention is to obviate the defects of existing constructions and to provide simple and efficient means for attaining the requisite increase of speed of the sand and air current at the outlet end of the conduit, and we attain this object by tapering the bore of the conduit so that the smallest part or end of the taper will discharge into the nozzle. The taper may extend the entire length of the conduit or only part thereof, but must be sufficiently long to effect the requisite speed acceleration.

Two embodiments of the invention are shown in the accompanying drawings in which, Figure 1 is a fragmentary sectional view of a conduit, the bore of which is tapered near its outlet end and Figure 2 is a similar view of a modified form in which the taper extends the entire length of the bore.

Referring to Figure 1 of the drawings, 10 is a merely conventional representation of a sand chest from which the sand is carried by air under pressure through the hose 11 and the nozzle 12. The bore 13 of the hose is

of uniform diameter from the chest 10 to approximately the point 13^a where the gradual taper effect or conicity starts and continues to approximately the point 13^b, adjacent the nozzle 12, where the bore has its 55 smallest diameter.

In Figure 2, the chest 10 communicates with the hose 11^a the bore or flow passage of which is gradually tapered or coned from the point 13^c of largest diameter to the point 13^d, adjacent the nozzle 12, of smallest diameter.

By the arrangement described and illustrated, no projecting obstacle is presented to the flow of the sand and air, but the gradual 65 decrease in the size or diameter of the flow passage constitutes highly efficient means for accelerating the speed and consequently the pressure of the issuing current of sand and air. 70

We claim:

In a device for projecting sand, the combination therewith, of a sand chest and a nozzle having a uniform bore, of a conduit connected to establish communication from 75 the chest to the nozzle and provided with a uniform bore at the sand chest end and tapered to its smallest diameter corresponding with the bore of the nozzle at the nozzle end, whereby sand is carried by air under pressure from said sand chest through said uniform and tapered bore of the conduit until it has reached its greatest velocity at the nozzle end. 80

In testimony whereof we affix our signatures. 85
